(57) CLAIM

The ornamental design for a U-neck long sleeve shirt with thumbholes, as shown and described.

DESCRIPTION

FIG. 1 is a front elevation view of a U-neck long sleeve shirt with thumbholes showing the present invention;

FIG. 2 is a side elevation view thereof;

FIG. 3 is an opposite side view thereof; and,

FIG. 4 is a rear elevation view thereof.

The broken line showing stitching is for the purpose of illustrating portions of the article and forms part of the claimed design.
